MEANS FOR DEFROSTING REFRIGERATING UNITS

Nathan F. Fretter, Cleveland Heights, Ohio

Application July 4, 1933, Serial No. 679,006

17 Claims. (Cl. 62—126)

This invention relates to refrigerating apparatus and more particularly to a novel means for defrosting the evaporator or refrigerating unit thereof.

5 My defrosting means is particularly, though not exclusively, intended to be used in connection with mechanically refrigerated apparatus or systems. The exemplified application of my invention consists of a refrigerator casing or cabinet wherein is provided a refrigerating unit which may include a series of trays removably placed therein.

10 One object of this invention is to provide improved means, that are relatively simple, durable and inexpensive in construction, for defrosting the refrigerating unit.

15 Another object is to provide an improved refrigerating unit defrosting means which can be operated quickly and without stopping the operation of the unit, thereby saving time and continuously maintaining a low temperature in the refrigerator.

20 Another object of the invention is to provide a removable shield for and in contact with the refrigerating unit and providing a surface on which frost may accumulate, so that its removal effects defrosting without affecting the temperature of the areas or chambers in the refrigerator and/or stopping the operation of the refrigerating unit.

25 Another object of the invention is to provide an improved defrosting device which lends itself to evaporators suspended from a horizontal, for example the top, wall of a refrigerator cabinet, such device being so constructed that it may be removed from the evaporator vertically downwardly or horizontally.

30 Further objects and advantages of the present invention will be apparent from the following description, references being had to the accompanying drawings, wherein two different forms of the invention are presented herein for the purpose of exemplification, but it will of course be understood that the invention is susceptible of other embodiments within the scope of the claims.

In the accompanying drawings:

35 Fig. 1 is a fragmentary sectional view through a portion of a refrigerator or cabinet showing therein a refrigerating unit and a defrosting means embodying my invention, parts being broken away.

40 Fig. 2 is a side elevation of the parts shown in Fig. 1.

45 Fig. 3 is a bottom plan view on the line 3—3 of Fig. 2.

50 Fig. 4 is a perspective view of the defrosting device.

55 Fig. 5 is a fragmentary section on the line 5—5 of Fig. 2.

Fig. 6 is a view similar to Fig. 1, but showing a modified form of construction.

Fig. 7 is a side view of the parts shown in Fig. 6.

Fig. 8 is a bottom plan view on the line 8—8 of Fig. 7.

Fig. 9 is a plan view of the device shown in Figs. 6, 7 and 8, with its sections separated.

Fig. 10 is a fragmentary front elevation of parts shown in Fig. 6, enlarged.

In the drawings, a portion of a refrigerator 10 is shown. 1 denotes generally the rear and side walls, 2 the top wall and 3 a portion of the front wall of the refrigerator, these walls being constructed in a manner well known in the art to minimize heat transfer. The front wall is provided with a door 4 providing access to the space 5 within the refrigerator and the refrigerating unit 6. 7 indicates ice trays of the ordinary construction and slidably outwardly and inwardly, the handles 8 serving as the operating means therefor.

The refrigerating unit, as shown is secured to the top wall 2, being suspended therefrom by suitable hangers 1'. In Figs. 1, 2 and 5, the refrigerating unit or evaporator 6 comprises a pair 25 of spaced chambers 6a and a coil arrangement 6' herein illustrated as consisting of an inner plate 6b and an outer corrugated plate 6c fixed to the inner plate in a well known manner to form the conduits 6e in communication with the chambers 6a. The coil arrangement, as shown in Figs. 1 and 2, is shaped to provide spaced parallel sides and a bottom, forming a space for the trays 7, the walls 6b being provided with laterally pressed ribs to form guides for the trays. The rear end of the coil arrangement below the chambers 6a may be provided with an end strip 9, which may form an abutment as later set forth. A suitable volatile liquid refrigerant is supplied to the chambers 6a, 6a, under control 40 of a float actuated valve (the supply pipe, float chamber, float and valve not being shown) of any desired construction. The chambers 6a, 6a, are provided with exhaust pipes 10, connected to a common exhaust pipe 11, which may lead to 45 the intake of a compressor (not shown). As is customary in refrigerating apparatus of this type, the volatile liquid refrigerant is supplied to the chambers 6a from which it flows into and through the conduits 6e and vaporizes. The vapors rise in these conduits into the chambers 6a where they become separated from the liquid and flow into the pipe 11, due to the suction effect therein.

50 Fig. 6 indicates my defrosting device adapted to be removably related to the coil arrangement 6' and having a cross sectional shape corresponding to the cross sectional shape of the coil arrangement 6' and preferably having corrugated walls complementary to the corrugations of the wall 60

6c, whereby intimate thermal contact between substantially the entire area of the walls of the device 12 with the walls 6c results and entrance of moisture (free moisture or vapor) between the device and coil arrangement 6' is prevented. Furthermore, the complementary corrugated walls serve as guide means in positioning the device. However, where the coil arrangement consists of a plurality of depending pipe loops or coils, 10 the corrugated walls of the device 12 will engagingly fit the pipe walls and close the spaces between them. The defrosting device 12 is preferably formed of sheet metal having relatively high heat conductivity, for example, aluminum alloy, 15 and is provided with means for detachably connecting it to the refrigerating unit, as shown in Figs. 1 and 2; and when so positioned it will be seen that vapor and free moisture circulating within the cabinet will, when precipitated as 20 frost, snow or ice, accumulate on the exterior surface of the device 12, which, being removable, permits defrosting to be effectively and quickly carried out. For example, the device 12, when removed may be thrust into a body of water, or 25 sprayed with water and then re-positioned, or another device may be substituted. As the frosting occurs on the exterior walls of the device 12, and not on the walls of the coil arrangement 6', removal of the food and/or stoppage of the 30 refrigerating unit 6 is not required, so that the refrigerated atmosphere in the cabinet is continuously maintained for an indefinite period.

Upon operation of the detachable means, the device 12 may be removed by moving it downwardly, or by expanding its sides its removal may be effected horizontally. To facilitate either operation, the device 12 is formed of a plurality of hingedly connected sections, preferably two L-sections 12a, 12a, whereby the sections may be initially swung laterally (see dotted lines in Figs. 1 and 4) to disengage them from the coil arrangement 6'. The hinge connections comprise plates 13 alternately spot-welded to the adjacent marginal portions of the sections 12a and provided with aligned knuckles to receive a pivot pin or rod 14, the outer end of which projects beyond the sections to form a handle 14a. The inner and outer hinge plates 13 and adjacent portions of the respective other sections 12a are provided with pairs of angles (spot-welded thereto) having related walls 15 which serve as stops to limit the lateral swinging of the sections 12a.

The detachable means comprise the following; 16 indicates a pair of aligned bearing members disposed at either side of the refrigerating unit adjacent the upper ends of the coil arrangement 6' and disposed outwardly of the plane in which the side walls of the device 12 are disposed when in position. Each member preferably consists of a plate spot-welded to the hangers 1' and provided with projecting spaced lugs 17, 17', the lower lug 17' forming a seat. 18, 18, indicate connectors swingably mounted on the free ends of the sections 12a and each having portions which removably engage the adjacent seats 17'. As shown in Figs. 2 and 4, each connector 18 has (a) an intermediate portion 18a rotatable in a knuckle 19 provided on the end of a wall 20 extending upwardly from the adjacent section 12a and (b) off-set end portions 18b adapted to be inserted between the lugs 17, 17', into the seats formed by the latter lugs. The outer end of the connector is provided with a handle 21. To position the device 12, it is engaged with the coil arrangement 6' against the abutment 8 and the off-sets 18b

are engaged in the seats 17'; next the handles 21 are operated to rotate the off-sets 18b in the seats 17', which operation swings the portions 18a upwardly and inwardly against the hangers 1'. As the portions 18a rotate in the knuckles 19 and are connected through the latter to the upper or free ends of the sections 12a, it will be seen that the upwardly and inwardly swinging movement of the portions 18a will move the latter inwardly beyond or past the centers of the seats 17'; accordingly an off-center or toggle action will result to securely engage the walls of the device against the coil arrangement 6' and the connectors will be locked in position. Operation of the handles in the opposite direction will release the connectors 18 and swing the sections 12a, 12a, outwardly away from the coil arrangement so that the device 12 may be removed.

Figs. 6 to 10, inclusive, show a modified form of construction in which the refrigerating unit 6x consists of a single volatile liquid chamber 6x' and the upper ends of the coil arrangement are turned inwardly, the liquid refrigerant being supplied by a pipe 22 and the gas or vapors being exhausted through a pipe 23 and the unit being suspended by a pair of hangers 1x. The lateral sides of each hanger 1x are extended and provided with inverted contiguous cam walls 24a, 24b, the purpose of which will later appear. As shown, the defrosting device 12x is shaped to fit the coil arrangement 6x' and carries at the upper end of each side wall a connector 18x having a handle 18x', each of said ends being provided with spaced knuckles 25 in which the adjacent connector rotates. Between the knuckles 25, the connector 18x is provided with off-sets 26, each in aligned relation to one of the cam walls and arranged to engage therewith when the adjacent connector is operated. In positioning in engagement with the coil arrangement 6x', with the off-sets 26 at the inner ends of the cam walls 24a, 24b. By operation of the handles 18x', the connectors 18x are rotated in the knuckles 25, the effect of which is to swing the off-sets outwardly into engagement with the cam walls 24a, 24b and as the operation of the handles continues the cam walls 24a, 24b acting through the off-sets 26 will force inwardly the end portions of the device 12x to the limit of their movement, the effect of which is to lock the connectors in operated position. In the reverse movement of the handles, the off-sets 26 will engage the cam walls 24a, 24b, which will serve to swing the sections of the device 12x away from each other, so that the device can be readily removed.

To those skilled in the art to which my invention relates, many changes in construction and widely differing embodiments and applications of the invention will suggest themselves without departing from the spirit and scope of the invention. My disclosures and the description herein are purely illustrative and are not intended to be in any sense limiting. 60

What I claim is:

1. In a refrigerating mechanism, the combination with an evaporator, of a sectional defrosting device formed of sheet metal and having a bottom and side portions arranged to fit over said evaporator in thermal contact therewith, and quick operating mechanism connected thereto for detachably securing said device in position. 65

2. In a refrigerating mechanism, the combination with an evaporator supported from its lengthwise surface, of a sectional defrosting device formed of sheet metal and fitting and having 70

ing thermal contact with said evaporator, and quick operating mechanism connected thereto for securing said device in position.

3. In a refrigerating mechanism, the combination with an evaporator, of a sheet metal device comprising hinged sections arranged to fit over said evaporator in thermal contact therewith, and means on the terminating ends of said sections for detachably securing said device in position, said sections being swingable about their hinges to permit removal and positioning of said device.

4. In a refrigerating mechanism, the combination with an evaporator, of a sheet metal device comprising hinged sections arranged to fit over said evaporator in thermal contact therewith, and means for detachably securing said device in position.

5. In a refrigerating mechanism, the combination with a support and an evaporator supported thereby, of a sheet metal device comprising hinged-together sections arranged to removably fit over and have thermal contact with said evaporator, and detachable means for securing said device in position.

6. In a refrigerating mechanism, the combination with a support and an evaporator supported thereby, of a sectional defrosting device formed of sheet metal and corresponding in cross sectional shape to the cross sectional shape of said evaporator and arranged to be positioned thereover in thermal contact therewith, and quick operating mechanism connected thereto for securing the said device in position.

35 7. In a refrigerating mechanism, the combination with a support and an evaporator supported thereby, of a sectional defrosting device formed of sheet metal and having a bottom and side portions arranged to fit over said evaporator in thermal contact therewith, and a crank actuating mechanism secured to each side portion for detachably securing said device in position.

8. In a refrigerating mechanism, the combination with a support and an evaporator supported thereby, of a sheet metal device comprising hinged sections arranged to fit over said evaporator in thermal contact therewith, and means on the terminating ends of said sections for detachably securing said device in position, said sections being swingable about their hinges to permit removal and positioning of said device.

9. In a refrigerating mechanism, the combination with a support and an evaporator supported thereby, of a sheet metal device comprising hinged sections arranged to fit over said evaporator in thermal contact therewith, and means on the terminating ends of said sections for detachably securing said device in position, said sections being swingable about their hinges to permit removal and positioning of said device and means for limiting the movement of said sections away from each other.

10. In a refrigerating mechanism, the combination with a support and an evaporator supported thereby, of a sheet metal device comprising a pair of hinged sections arranged to fit over said evaporator in thermal contact therewith and swingable laterally to permit removal of

said device, the pivot pin of the hinges for said sections being extended to form a handle, and means for detachably securing said device in position.

11. In a refrigerating mechanism, the combination with a refrigerating unit comprising a chamber and a coil arrangement, of a sheet metal device having corrugated side and bottom walls arranged to fit over said coil arrangement in thermal contact therewith, said device comprising hinged together L-sections and detachable means for connecting the upper ends of said sections to the upper portion of said coil arrangement.

12. In a refrigerating mechanism, the combination with a support and an evaporator supported thereby, of a sheet metal device fitting and having thermal contact with said evaporator, and detachable means for securing said device in position, said means comprising seat members and connectors having portions rotatably mounted on said device and off-set portions arranged to detachably engage said seat members and swingable into locking position.

20 13. In a refrigerating mechanism, the combination with a support having supporting elements and an evaporator supported by said elements, of a sheet metal device comprising relatively movable connected sections having thermal contact with the heat exchange walls of said evaporator and removable therefrom to effect defrosting, and means engaging said supporting elements for detachably securing said device in position.

25 14. In a refrigerating mechanism, the combination with a support having supporting elements and an evaporator supported by said elements, of a sheet metal device corresponding in cross sectional shape to the cross sectional shape of said evaporator and comprising hinged sections and arranged to be positioned over and in thermal contact with said evaporator, and detachable means engaging said elements for securing said device in position.

30 15. In a refrigerating mechanism, the combination with an evaporator, of a device comprising hinged-together sections shaped to thermally contact therewith and adapted to serve as frost collecting surfaces, and a cam mechanism for relatively moving said sections to clamp and release them in relation to said evaporator.

35 16. In a refrigerating mechanism, the combination with an evaporator, of a device comprising hinged-together sections shaped to thermally contact therewith and adapted to serve as frost collecting surfaces, and a toggle-joint mechanism for relatively moving said sections to clamp and release them in relation to said evaporator.

40 17. In a refrigeration mechanism, the combination with an evaporator, of a removable defrosting device formed of heat conducting material and comprising relatively movable connected sections arranged to engage with and enclose the side walls of the evaporator from end to end thereof, and attaching means carried by the said sections.

NATHAN F. FRETTER.
